GLUED BAG AND METHOD OF PRODUCING
THE SAME

Clyde K. Billeb, Shorewood, Wis., assignor to Milprint, Inc., Milwaukee, Wis., a corporation of Delaware

Application June 21, 1947, Serial No. 756,253

3 Claims. (Cl. 229—53)

1

The present invention relates generally to improvements in the art of manufacturing bag-like receptacles and relates more specifically to an improved bag structure and to an improved method of and apparatus for producing the improved structures or articles.

It has heretofore been common commercial practice to manufacture bags for merchandising diverse commodities, of heat sealable ribbon stock, by initially forming the stock into an elongated flat tube, by thereafter severing the tube into sections of suitable length, by subsequently folding an end of each flattened tube section upon itself, and by finally applying heat and pressure to each folded over portion to heat seal the end of the tube section and to thus produce a bag having a thoroughly sealed bottom. In some cases and especially where a liquidtight bottom was required, the tube end has been double folded and heat sealed, and while these prior heat sealing methods are quite satisfactory as applied to stock which is capable of being sealed with the mere application of heat and pressure, such stock is not always available and may not be satisfactory for the intended use. It frequently happens that other types of non-heat-sealable, relatively inexpensive, and otherwise more suitable packaging stock is desired, and in such cases the bag seams and bottom must be adhesively sealed with the aid of glue; but considerable difficulty has heretofore been encountered in producing such glued bottom bags and in maintaining the bag bottoms tightly and permanently sealed against leakage when the bags were filled with commodity.

It is therefore a primary object of my present invention to provide an improved commodity receiving bag formed of flexible and relatively impervious stock, and having a bottom adhesively sealed so as to effectively prevent leakage or egress of commodity and ingress of air or other substances therethrough.

Another important object of this invention is to provide an improved method of producing hermetically sealed glued bottom bags from relatively thin ribbon stock, in rapid succession and at moderate cost.

A further object of the present invention is to provide simple and highly efficient apparatus for effecting automatic exploitation of the improved bag producing method, and for manufacturing the improved bags in an expeditious and reliable manner.

These and other more specific objects and ad-

vantages of the invention will be apparent from the following detailed description.

A clear conception of the several steps involved in the improved method of producing the new glued bags, and of typical apparatus for effecting commercial exploitation of the method, may be had by referring to the drawings accompanying and forming a part of this specification wherein like reference characters designate the same or similar parts in the various views.

Fig. 1 is a diagrammatic side view of a typical installation for automatically producing my improved glued bags in rapid succession;

Fig. 2 is an enlarged diagrammatic side view of the bag bottom folding and glueing rotor constituting a part of the installation of Fig. 1;

Fig. 3 is a further enlarged diagram depicting the successive bag bottom forming steps involved in my new bag production method;

Fig. 4 is a plan view of the bottom portion of one of the improved bags produced by my present method; and

Fig. 5 is a considerably enlarged fragmentary perspective view of the bottom portion of one of the improved bags, showing the sealing folds partially disrupted to clearly reveal the bag bottom formation.

While the improvement has been specifically described herein as being advantageously applicable in the production of double-folded glued bottom bags formed of a particular type of thin and transparent non-heat-sealable material, it is not my desire or intention to unnecessarily limit the invention by virtue of this restricted application, since other suitable materials may also be utilized.

In accordance with my present improved method of producing the new bags, I initially convert a continuous ribbon of relatively impervious, thin and flexible sheet stock into an elongated tube, by folding the opposite edges of the tube inwardly to overlapping position, and by adhesively uniting the overlapped ribbon edges. I then sever the tube into successive sections of suitable length, after which the corresponding end portion of each tube length is folded along a transverse line and the fold is adhesively attached to the adjacent outer wall of the tubular section, to provide a temporary bottom closure having at least four thicknesses of the sheet stock throughout its area. The preliminarily folded and glued bottom portion of each bag section, is thereafter folded upon itself along a line extending across the bag intermediate the lower and upper edges of the initial fold, and the re-

sultant final fold is adhesively connected to the outer surface of the remainder of the preliminary fold and to the same outer wall of the bag beyond the zone of attachment of the original fold, thereby completing the bag bottom. The final bag bottom closure thus produced, has at least eight thicknesses of sheet material throughout an area extending upwardly along the bag for a considerable distance, and also has at least as many thicknesses of stock at the extreme lower end thereof; and each bag closure is hermetically sealed along three extensive superimposed areas of adhesive, thus providing a triple seal.

When carrying on commercial exploitation of my improved bag producing method, I prefer to utilize an installation substantially as shown diagrammatically in the drawings, in order to rapidly, automatically, and effectively construct the successive bags. Referring to Figs. 1, 2 and 3 of the drawings, the initial thin and flexible ribbon 8 of any relatively impervious sheet stock, such as regenerated cellulose, may be supplied in the form of a rotatably supported roll 9 from which the ribbon 8 may be constantly withdrawn by a set of draw rolls 10, supplied along an edge with glue or other adhesive by a center seam glue wheel 11, and converted into a constantly advancing flat tube having a longitudinal glued seam 12 at the overlapped ribbon stock edges by a tube forming unit 13. The tube thus initially formed may be provided with opposite inwardly extending side pleats 15 extending parallel to the seam 12 as in Fig. 4, and immediately after the seam 12 has been completed, the advancing tube may be delivered by another set of draw rolls 16 to a cut-off knife assembly 17 which severs the continuous tube into successive tube or bag sections 18 of suitable length, in a well known manner.

The successive tubular bag sections 18 are delivered by a set of breaker rolls 19 from the severing zone to the upper rear portion of the periphery of a rotating bag blank conveying and bottom forming cylinder or rotor 20 having two revolving cylindrical tuckers 21 associated therewith. This cylindrical rotor 20 is rotatable within a frame and is provided with an annular series of equally spaced peripheral gaps 22 within each of which a clamping plate 23 is swingably disposed for oscillation about the axis of a carrier pivot 24, so that each plate 23 may clampingly cooperate with the opposite sides of its confining gap 22. While only two of these gaps 22 and plates 23 have been shown in the diagrams, there are in fact six or more sets of gaps and plates spaced uniformly about the axis of the rotor 20, and the supporting pivots 24 of these plates are mounted in and are revolvable by the rotor. The outer ends of each of the pivots 24 are provided with rock levers 25 each having a roller 26 journalled in its swinging end, and these rollers 26 coat and are constantly urged into engagement with fixed cams 27, by means of tension springs 28. This cam and lever assemblage is such that when the rotor 20 is revolving in the direction indicated by the arrow, the successive clamping plates 23 will be swung into clamping engagement with the opposite sides of their confining slots or gaps 22 at timed intervals so as to clamp and to release various lower end portions of the successive bag blanks or sections 18.

The two revolvable cylindrical tuckers 21 which are disposed above and forwardly of the rotor are rotatable in unison with but in directions opposite to the direction of rotation of the rotor

cylinder 20, and each tucker 21 carries a pair of diametrically opposite radial tucking blades 30 which are adapted to enter and leave the successive rotor gaps 22, and which are also cooperable with adjacent adhesive or glue supply rollers 31 so as to receive adhesive therefrom. As shown in Fig. 2, there is a glue transfer roller 31 provided for each tucker 21, and the glue transfer and tucking blades 30 are adapted to enter the successive rotor slots 22 on opposite sides of the confined and oscillating clamping plates 23. The tuckers 21 and the glue transfer rollers 31 are of relatively well known construction, but the manner in which these tuckers 21 coat with the rotor clamps and with the successive bag blanks 18 to provide triple bottom seals, is new, and the rotor cylinder is embraced between tuckers by a stationary wall and is provided at its lower front portion with a pick-off blade 32 for removing the completed bags therefrom and for delivering the finished product to a dryer or the like.

During normal operation of the equipment hereinabove described, and while exploiting my new bag producing method, the draw rolls 10, 16 are operating to constantly withdraw flat ribbon stock 8 from the supply roll 9, and the glue roll 11 is functioning to apply adhesive to the longitudinal side edge portion of the advancing ribbon, 30 while the forming unit 13 converts the stock band into a continuous elongated flat tube having a central seam 12 and opposite side pleats 15 extending throughout its entire length, as shown in Fig. 4. Upon delivery of this flattened tube 35 from the second set of draw rolls 16, it is severed into predetermined lengths or tubular sections 18 by the knife assembly 17, whereupon the successive severed sections pass between the breaker rolls 19 and are deposited upon the periphery of the rapidly revolving rotor 20, being guided by the rotor embracing wall in a well known manner, into the paths of revolution of the clamping plates 23 and of the tucker blades 30, preparatory to the application of the improved bottom closures.

The successive steps involved in the formation of the successive triple bottom seals, are illustrated diagrammatically in Fig. 3, and as shown at the extreme right, step I consists of the provision of a transverse fold or tuck 33 some distance from one end of each advancing bag section, by causing one of the glue coated tucker blades 30 of the upper tucker 21 to enter the adjacent rotor gap 22 to the left of the corresponding clamping blade 23. In addition to forming the tuck 33, the blade 30 deposits glue into this tuck; and as soon as the tuck 33 has been formed, the blade 23 is swung toward the left and compresses and clamps this tuck while the tuck producing blade 30 is withdrawn from the gap 22 as indicated by step II, thus also spreading the glue and projecting the end portion 34 of the bag blank 18 outwardly perpendicular to the main body thereof. Immediately following step II, the outwardly projecting portion 34 of the advancing tube section 18 is folded back and is pressed and glued against the adjacent centrally seamed outer wall 35 of the bag blank as shown in step III, by causing the portion 34 to engage the rotor embracing stationary wall of the frame located between the tuckers, in a well known manner, thereby providing the preliminary bag bottom seal.

Each initial bottom seal is thereafter provided with a second transverse tuck 36 and glue application as depicted by step IV, by causing one of the glue coated tucker blades 30 of the lower tucker 21 to enter the same rotor gap 22 to the

right of the same clamping blade 23. In addition to forming the tuck 36, this final tucking blade 30 deposits glue into this tuck, and immediately following the formation of the tuck 36 the previously folded remote end portion 37 of the bag 18 is projected outwardly perpendicular to the bag body and the tuck 36 is compressed, by causing the clamping blade 23 to swing toward the right, as indicated by step V. While the final tuck 36 is thus clamped, the folded portion 37 of the bag section 18 will be folded back and pressed and glued against both the end part 38 and the seamed outer wall 35 of the bag 18 as shown in step VI, by another stationary frame wall near the rotor periphery, thus completing the bag bottom closure and providing a triple glued seal for each of the successive bags. The clamping plate 23 will be subsequently released, and the successive finished bags 18 will be delivered to the dryer by the pick-off blade 32 in an obvious manner.

The improved bag producing method is thus carried on continuously, effectively, and automatically with the aid of simple equipment, to complete successive improved bags 18 such as shown in Figs. 4 and 5, in rapid succession. Each of the final bags 18 is provided with an adhesive seal between the folded portions 34, 37, with a second adhesive seal between the bag wall 35 and the remote end portion 38 of the blank, and with a third adhesive seal between the folded portion 34 and the wall 35 and portion 38, as clearly shown in the partially disrupted perspective view of Fig. 5. By utilizing relatively impervious stock or material in the production of these bags, the triple bottom seal thus provided will hermetically seal the bag bottom against egress or ingress of air, vapor or other fluent substances; and by forming the bags 18 with the bottom folds overlapping the seams 12, these seams are thoroughly reinforced and protected against opening when the bags are finally filled with commodity. While the normally concealed sealing portions 38 may be made of the same length as the covering portions 34, 37, such lengthening serves no useful purpose and considerable stock is saved by shortening these portions 38 as shown; and when the bags 18 are provided with side pleats 15 the lower outer corners of the bottom of each bag will have sixteen thicknesses of stock while the medial bottom portions will have eight thicknesses, thereby providing a relatively rigid bottom even when relatively thin and flexible sheet stock is utilized.

From the foregoing detailed description it will be apparent that my present invention provides an improved glued bottom bag adapted to be manufactured from relatively inexpensive stock, and the bottom of which is thoroughly reinforced and sealed against leakage. By utilizing the improved method in the manufacture of these bags, the speed or rate of production may be enhanced to a maximum and the cost may be minimized; and the apparatus shown and described herein, while embodying many well known features is reliable and highly efficient in operation, and may be readily modified and adjusted to produce the improved bags in various shapes and sizes. The invention has in fact gone into extensive and highly successful commercial use especially for the production of flat pleated bags 18 from transparent and relatively thin and flexible regenerated cellulose and the like, and these commercial bags 18 have proven very satisfactory

for the purpose of packing and merchandising diverse commodities which are amply protected and maintained in fresh and wholesome condition by virtue of the improved triple sealed bottom construction. The improved flat bags may be decorated by printing or otherwise, with suitable indicia, and the side pleats 15 materially enhance the holding capacities of the receptacles.

It should be understood that it is not desired to limit this invention to the exact steps of the production method or to the precise details of construction of the bags, herein described and shown, for various modifications within the scope of the appended claims may occur to persons skilled in the art; and it is also contemplated that specific descriptive terms used herein be given the broadest possible interpretation consistent with the disclosure.

I claim:

- 20 1. An article of manufacture comprising, a bag having a flat substantially rectangular tubular body one end of which has substantially coinciding free edges, said one end being initially folded and glued to the outer surface of the tubular body, and said initially folded portion being refolded in the same direction along a fold line located between the transverse center line thereof and the said free edges and glued against a portion of the initial fold and directly against the tube surface.
- 25 2. An article of manufacture comprising, a bag having a flat substantially rectangular tubular body provided with a longitudinally seamed wall and one end of which has substantially coinciding free edges, said one end being initially folded and glued to the outer surface of the seamed wall, and said initially folded portion being refolded in the same direction along a fold line located between the transverse center line thereof and the said free edges and glued against a portion of the initial fold and directly against the tube surface.
- 30 3. The method of producing glued bottom bags, which comprises, forming a flat substantially rectangular tubular blank having substantially coinciding free edges at one end thereof, initially transversely folding said end of the blank and gluing the fold against the adjacent outer surface of the tube, and refolding the initially folded portion in the same direction along a fold line located between the transverse center line thereof and the said free edges and gluing the second fold against a portion of the initial fold and directly against the tube surface.
